NUT-LOCK.

SPECIFICATION forming part of Letters Patent No. 782,900, dated February 21, 1905.

Application filed June 30, 1904. Serial No. 214,706.

To all whom it may concern:

Be it known that we, JOHN C. DENT, JOSEPH DENT, Sr., and JOSEPH DENT, Jr., citizens of the Dominion of Canada, residing at Bothwell, 5 in the county of Kent, Province of Ontario, Canada, have invented certain new and useful Improvements in Nut-Locks; and we do declare the following to be a full, clear, and exact description of the invention, such as will 10 enable others skilled in the art to which it appertains to make and use the same, reference being had to the accompanying drawings, and to the figures of reference marked thereon, which form a part of this specification.

15 This invention relates to nut-locks, and particularly to the locking of nuts of the bolts that pass through the fish-plates which unite the ends of railway-rails; and it consists in the construction and arrangement of parts herein- 20 after fully set forth, and pointed out particularly in the claims.

The object of the invention is to provide simple and efficient means applicable to nuts in common use upon railway-bolts whereby 25 said nuts may be prevented from turning by reason of the jar and vibration incident to the passage of a train along the track, the arrangement being such as to enable the locking device to be readily placed upon the nuts and 30 quickly and easily removed.

The above object is attained by the structure illustrated in the accompanying drawings, in which—

Figure 1 is a perspective view of the joined 35 ends of two railway-rails, showing the application of our invention. Fig. 2 is a fragmentary view in perspective of the joined ends of the locking-bar, showing the manner in which the sections of the bar may be drawn 40 together and held against longitudinal separation. Fig. 3 is a view in elevation showing the members of the locking-bar separated. Fig. 4 is a transverse section as on line 4-4 of Fig. 1. Fig. 5 is a fragmentary view in detail showing the manner in which the hook at the end of the locking-bar engages in a recess of the fish-plate. Fig. 6 is a fragmentary

view, partly in longitudinal section, showing the meeting ends of the sections of the locking-bar detached.

Referring to the characters of reference, 1 designates the service-rails, and 2 the fish-plates which are used to unite said rails at the joint. Passing through the fish-plates and the web of the rails are the ordinary bolts 3. 55 Screwing onto said bolts are the nuts 4. For the purpose of preventing said nuts from turning on the bolts after they have been set there is employed a locking-bar made in two sections 5 and 6, joined at the center. To 60 connect the meeting ends of said bar, section 5 is provided in the inner end thereof with a mortise 7. Formed in the opposite walls of said mortise are the inclined ways 8, which extend downwardly and terminate in a straight lower 65 portion 9, as shown in Fig. 2. Projecting from the inner end of the section 6 of the locking-bar is a tenon 10, having pins 11 extending laterally therefrom, the opposite ends of which are adapted to engage in the opposed inclined ways 70 8 as the tenon is placed in said mortise from the top. As the parts are forced together the pins travel down the inclined ways and draw the ends of the sections of the bar together until the straight portion 9 of said ways is encountered, which the ends of the pins enter and 75 lock the sections of the bar against longitudinal separation. Upon the top of the tenon is a cap 12, which closes the mortise-opening.

In the under edge of the sections of the locking-bar are the notches or apertures 13, spaced to correspond with the nuts 4 on the transverse bolts which unite the rails. Said notches are formed with an outer vertical face, an upper horizontal face adapted to engage the sides 85 of the nuts, and with an inclined inner face 14, which allows of a longitudinal movement of the sections of the bar in adjusting them upon the nuts. At the outer ends of the sections of the locking-bar are the engaging 90 hooks 15, which enter recesses in the ends of the fish-plate and lock the sections of said bar from lateral displacement. In placing this locking-bar upon the nuts the hooks at the ends

are engaged in the recesses in the fish-plate and the tenon of one section inserted from the top in the mortise of the other section and said parts forced one into the other, which 5 operation draws them together longitudinally, causing the hooks 15 to engage firmly in the recesses of the fish-plate and the notches to engage the nuts in a manner to prevent them from turning, as shown in Fig. 1. To remove 10 the locking-bar, the meeting ends of the sections thereof are disengaged by raising the inner end of section 6 until the ends of the pin engage the inclined slot, when a further upward movement of said section will cause a 15 longitudinal separation of the sections as the tenon is withdrawn from the mortise, thereby relieving the hooks at the ends of said sections and enabling them to be removed.

Having thus fully set forth our invention, 20 what we claim as new, and desire to secure by Letters Patent, is—

1. In a nut-lock, the combination with the bolts and nuts, of a two-part locking-bar having open notches in its under edge to engage 25 said nuts, the meeting ends of the parts of said bar having engaging interlocking members for detachably locking said parts together.

2. In a nut-lock, the combination with the bolts and nuts, of the two-part locking-bar having open inclined notches to engage the 30 nuts, each of said parts having a member at the end adapted to engage the fish-plate and said parts having integral interlocking members at the meeting ends for detachably uniting them.

3. In a nut-lock, the combination with the bolts and nuts, of the two-part locking-bar, each part having a hook at the end adapted to engage the fish-plate, there being in one part a mortise and upon the other part a tenon 40 adapted to enter said mortise, there being in the wall of the mortise an inclined way and a pin in the tenon adapted to engage in said way, the under side of said locking-bar having notches adapted to engage over the nuts. 45

In testimony whereof we sign this specification in the presence of two witnesses.
